Maynard D. Lawrence, Detroit, Mich., assignor to Berkley Machine Products, a copartnership composed of Harold L. Cox, Detroit, and Raymond A. Chabot, Milford, Mich.

Application September 1, 1954, Serial No. 32,124

Term of patent 14 years

(Cl. D3—10)

To all whom it may concern:

Be it known that I, Maynard D. Lawrence, a citizen of the United States, residing at Detroit, State of Michigan, have invented a new, original, and ornamental Design for a Game Belt, of which the following is a specification, reference being had to the accompanying drawing, forming a part hereof.

Fig. 1 is a plan view of a game belt showing my new design;

Fig. 2 is a top edge view thereof; and

Fig. 3 is a sectional view taken on the line 3—3 of Fig. 1.

The game bag and cartridges shown in broken lines on the drawing are for illustrative purposes only.

I claim:

The ornamental design for a game belt, as shown and described.
